F. F. METCALF,
NECKTIE STRETCHER,
APPLICATION FILED JULY 19, 1919.

1,346,552.

Patented July 13, 1920.

INVENTOR:
Fred F. Metcalf,
BY *W. D. Duvall*, ATTORNEY.

UNITED STATES PATENT OFFICE.

FRED F. METCALF, OF CHICAGO, ILLINOIS.

NECKTIE-STRETCHER.

1,346,552.

Specification of Letters Patent. Patented July 13, 1920.

Application filed July 19, 1919. Serial No. 311,993.

To all whom it may concern:

Be it known that I, FRED F. METCALF, a citizen of the United States, residing at Chicago, in the county of Cook and State 5 of Illinois, have invented a new and useful Necktie-Stretcher, of which the following is a specification.

This invention relates to an improvement in that class of neck-tie stretchers consisting of an expansible frame formed of wire and adapted to be inserted in the larger end of what is known as the "four-in-hand tie" for the purpose of eradicating wrinkles therefrom caused by use of the tie.

15 The objects and advantages of the invention together with the novel features thereof will hereinafter appear and be particularly pointed out in the appended claims.

Referring to the drawing, in which I have 20 illustrated my invention in front elevation, it will be seen that the same is formed of a single piece of resilient or spring-wire of suitable length and gage, bent at its middle to form preferably a coil 1, from which 25 diverge upwardly a pair of opposite corresponding and preferably slightly outwardly curved resilient terminals 2.

At a suitable distance from the eye or 30 coil 1, each of these terminals 2, may be coiled as at 3, these latter coils preferably being somewhat smaller than the coil 1. Beyond the coils 3, the terminals 2 are disposed or bent substantially at right-angles to the remainder of the terminals or toward 35 each other so as to form overlapping transverse ends 4, which pass by one another and are maintained in freely slidable connection by some suitable means, in this instance, a light sheet-metal sleeve 5, centrally located 40 with relation to the device and beyond the ends of which the bent terminals 4 extend. I prefer to form at the end of each of the transversely disposed portions 4, right-angularly disposed eyes 6, the eye of one terminal loosely receiving the transverse portions of the companion-terminal, so that as 45 will be seen, the eye of one terminal is disposed in a direction opposite to that of the eye of the companion-terminal. These eyes, 50 it will be seen, in addition to forming a slidable connection between the transverse portions of the two terminals, also constitute stops by abutting against the ends of the sleeve 5, so that the possibility of an 55 entire separation of the terminals 2 is avoided.

For convenience I may provide the sleeve 5 with a ring or eye 7, for the purpose of affording a means of suspension.

The tendency of the terminals 2, are to 60 expand or spread apart, and in use the smaller end (the coil 1) is inserted in the open larger end of the four-in-hand tie, the device being pushed into the tie, during 65 which operation the spring terminals 2 will duly yield and conform to the contour of the tie. If the tie, which has become wrinkled from use, especially if slightly damped is permitted to remain upon the stretcher, all wrinkles will have become 70 eradicated, and when the stretcher is removed the tie will lie flat and smooth as when new and show no effects of previous wear. During the time the stretcher is in 75 position in the tie the latter will be constantly and lightly stretched owing to the tendency of the device to expand, so that the material of the tie will be constantly under yielding tension.

It will be obvious that there may be substituted for the sleeve 5, and suspension-eye 7 thereof, other convenient means for serving the same functions, or that these parts may be entirely omitted, in which case the eyes 6 alone would be depended upon 80 to form the sliding connection and stops between the terminals 4. Also that where the sleeve 5 is employed the ends of the terminals 4 may be otherwise formed to constitute stops or they may be left plain. I 85 prefer however to employ the eyes 6 for the purposes mentioned and also for the reason that they prevent any likelihood of the ends of the stretcher engaging with and injuring the fabric of the tie. For the same reason 90 and also because they lend greater resiliency I also prefer to employ the coils 1 and 3, 95 rather than mere bends.

It is obvious that while the stretcher herein shown and described is especially adapted 100 for neck-ties, yet by employing a pair of the same and modifying the proportions herein shown, said device is applicable to trousers for the purpose of straightening out the legs and eliminating the wrinkles 105 and "knees" which form therein as a result of wear. I do not therefore wish to be understood as limiting my invention in its use to neck-ties, but hold that I may modify the proportions of the same for use as a 110 trouser or other garment-stretcher without departing from the spirit of the invention.

Having described my invention, what I claim is:

1. A stretcher for the purpose described, the same being formed of a single length of spring-wire bent at an intermediate point to form a coiled eye and a reduced entering-end, upwardly disposed beyond said eye to form opposite diverging companion terminals, the latter at corresponding points being bent to form corresponding coils and beyond them inwardly laterally disposed overlapping portions terminating in oppositely disposed eyes, the eye of one of said portions receiving the laterally disposed portion of the companion terminal, whereby a freely slideable connection between said overlapping portions is formed, and a sleeve loosely receiving said overlapping portions of the terminals and in which the latter are freely slideable, said sleeve being provided with a suspension-eye and being positioned between the eyes of the overlapping portions
2. A stretcher for the purpose described, the same being formed of a single length of spring-wire bent at an intermediate point to form a reduced entering-end and beyond said point upwardly disposed to form opposite diverging companion terminals yielding 30ingly expanding toward their upper ends, said terminals being bent at corresponding distances from said entering-end to form companion inwardly disposed transverse overlapping portions the end of each of which is bent to form an eye loosely receiving the opposite companion portion, and a sleeve mounted upon and receiving said portions between the eyes and in which said portions are loosely and freely slideable, the 35 ends of the sleeve serving as abutments for the eyes of said portions.

FRED F. METCALF.
